GOLF PUTTER

Victor De Carlo, 514 Lookout Ave., Hackensack, N.J.

Filed Dec. 12, 1962, Ser. No. 72,815

Term of patent 14 years

(Cl. D34—5)

FIG. 1 is an elevational view of the golf putter showing my new design,

FIG. 2 is a plan view of the putter head, and

FIG. 3 is a side view taken on line 3—3 of FIG. 2.

The shaft has been omitted from FIGS. 2 and 3 for convenience of illustration.

The characteristic feature of my design resides in the horn-shaped leg on the putter head as shown.

This is a continuation in part of my original application, Serial No. D. 68,991, filed February 26, 1962 (now abandoned).

I claim:

The ornamental design for a golf putter, as shown and described.
